UNITED STATES PATENT OFFICE.

DAVID S. MORRELL, OF OLDTOWN, MAINE.

ARTICLE HOLDER.

Application filed March 28, 1923. Serial No. 628,310.

To all whom it may concern:

Be it known that I, DAVID S. MORRELL, a citizen of the Dominion of Canada, residing at Oldtown, in the county of Penobscot and State of Maine, have invented certain new and useful Improvements in Article Holders, of which the following is a specification, reference being had to the accompanying drawings.

19. This invention relates to article holders and more particularly to a device for supporting articles having round or substantially round handles.

An important object of the invention is
15 to provide a device of this character with
which the handle of the article may be
readily engaged and disengaged and which
will support with equal efficiency articles
the handles of which are of different diam-
20 eters within predetermined limits.

A still further object of the invention is to provide a device of this character which may be very cheaply produced and which is durable and efficient in service.

25 These and other objects I attain by the construction shown in the accompanying drawings, wherein for the purpose of illustration I have shown a preferred embodiment of my invention and wherein:—

30 Figure 1 is a perspective view showing an article holder constructed in accordance with my invention;

Figure 2 is a longitudinal sectional view therethrough;

35. Figure 3 is a transverse section therethrough.

Referring now more particularly to the drawings, the numeral 10 indicates an attaching plate formed to provide spaced upstanding flanges 11. Adjacent one end the flanges 11 are correspondingly notched, as indicated at 12, and between such end and the notch a pivot 13 is mounted in the flanges and has rotatably mounted thereon a disk 14, the periphery of which extends into the notch 12 for a short distance. A lock plate 15 is provided, having formed in one end thereof a notch 16 forming spaced arms 17 and 18. The plate is provided 50 with a longitudinally extending slot 19, one handle may be removed by applying thereto sufficient pressure to overcome the action of the spring 21 and force the plate 15 longitudinally until the base of the notch 16 of the same is sufficiently spaced from the periphery of the disk to permit passage of the handle past the central point, at which time the handle may be readily removed. 95 Many changes being possible in the construction as hereinbefore set forth without materially departing from the spirit of my invention, I do not limit myself to such specific structure as hereinbefore set forth 100 except as hereinafter claimed. 105

I claim:—

1. In an article holder the combination with a pivotally mounted plate having a longitudinally extending slot through which the pivot thereof extends, a support, a roller rotatably mounted upon the support adj-

cent one end of the plate, said end of the plate having a notch formed therein and means urging the plate longitudinally toward the roller and yieldable means normally maintaining one edge of the plate in alignment with the roller.

2. In a device of the type described, a support including spaced flanges having corresponding notches formed therein, a roller pivotally supported between the flanges at one side of the notch and having the periphery thereof extending into the notch, a plate pivoted intermediate the flanges at the opposite side of the notch and likewise extending into the notch at one end, said plate being provided at said end with a pair of spaced arms, means normally maintaining the plate with one of the arms thereof in approximate alignment between the pivot of the plate and the pivot of the disk and in proximity to the disk, the pivotal mounting of said plate permitting the shifting thereof upon its longitudinal axis.

3. In a device of the type described, a support including spaced upstanding flanges correspondingly notched adjacent one end thereof, a pivot mounted in said flanges between the notches thereof and the adjacent end, a disk mounted upon said pivot, a pivot mounted in said flanges adjacent the opposite ends thereof, a plate having a longitudinally extending slot receiv-

ing said pivot, a spring in said slot abutting the pivot tending to force the plate toward said disk, a spring engaging a support between the flanges and secured to said plate and tending to force the end of the plate next adjacent the disk outwardly from the support, said plate having the end thereof next adjacent said disk notched to provide spaced arms, means limiting the movement of the plate under the influence of the last named spring with one of the arms in proximity to the periphery of the disk.

4. In a device of the type described, a support having a notch formed therein, a roller pivotally mounted upon the support at one side of the notch and having the periphery thereof extending into the notch, a plate pivoted to the support at the opposite side of the notch and having its free end extending into the notch, said plate having said end thereof formed with a notch, means normally maintaining the plate with one edge thereof in approximate alignment between the pivot of the plate and the pivot of the roller and in proximity to the roller, the pivotal mounting of said plate permitting bodily shifting of the plate toward and away from said roller and a spring urging the plate toward the roller.

In testimony whereof I hereunto affix my signature.

DAVID S. MORRELL.
